VALVE FOR COLLECTING AND ELIMINATING SALIVA FROM MUSICAL WIND INSTRUMENTS

Francisco Di Biasio, Santa Fe City, Argentina

Application October 30, 1956, Serial No. 619,325

6 Claims. (Cl. 84—397)

The invention relates generally to musical instruments, and more particularly to a device for collecting and eliminating saliva from a musical wind instrument. The invention provides for a device which is put into the musical wind instrument for the purpose of eliminating therefrom saliva which collects in the interior of the tubes as a result of the musical performance. The advantages provided thereby are the following:

The performer may use the musical instrument without any need of discharging therefrom saliva for a lengthy time.

The task of discharging saliva from a wind instrument has long been found to complicate and to impair the performance of a musical work, especially if it is of a long duration and particularly when the performer is a solo concertist. Periodic discharging has not only been found inconvenient in the past, but also detrimental to the instrument, causing wear and tear owing to the frequent disassembling and re-assembling. The accumulation of saliva in the instrument, during the intervals between discharges, has heretofore caused deterioration of the instrument. Yet, unless the saliva is discharged on time, the air will produce bubbles from the saliva with attendant disadvantages for the quality of musical performance.

The instant invention eliminates the need for periodic discharges. It thereby renders possible that during concerts of long duration the playing of the wind instruments can be continued without any need of discharging saliva from the wind instruments during the musical performance, as it permits the accumulated liquid to be discharged from the instrument only at the end of the concert.

So that the present invention may be understood clearly and easily carried into practice in its fundamental concept, a description of a preferred form of embodiment is given hereafter, wherein reference is made to the accompanying drawings which form part hereof, everything by way of example only and without limitation of the invention thereto.

In said drawings:

Figure 1 is a fragmentary elevational view of the device, applied to a wind instrument at the most convenient place thereof (which varies in accordance with the type and the shape of the instrument);

Figure 2 is an elevational, partly schematic, view of a tubular piece which is inserted in the interior of a tube of the instrument;

Figure 3 is an elevational view similar to Figure 2, but with the addition of a piece in the shape of a channel which is perforated beneath, and its relative position;

Figure 4 is a sectional view, taken on line 4—4 of Figure 3;

Figure 5 is a fragmentary longitudinal sectional view which shows a tubular discharge projection on the wind instrument for adapting thereto the instant device;

Figures 6 and 6a respectively are an elevational view and a bottom view, of a tube which will be threaded into

2

the interior of the tubular projection showing Figure 5;

Figure 7 is an extended elevational view of a tubular piece which is applied coaxially to the said tubular projection;

5 Figure 8 is a sectional view taken along line 8—8 of Figure 7;

Figure 9 is a sectional view taken on line 9—9 of Figure 7;

10 Figure 10 is a large scale elevational view of a coupling piece;

Figures 11 and 12 are large scale side elevational views of a tubular support for a valve to be removably mounted on the coupling piece of Figure 10;

Figure 13 is a large scale view of a valve;

15 Figure 14 is a large scale elevational view of a tubular end piece which is manually operable for the discharge of saliva from the device;

Figure 15 is a longitudinal sectional view taken on line 15—15 of Figure 14;

20 Figure 16 is a plan view of the movable end piece which has been shown in Figure 14; and

Figure 17 is a longitudinal fragmentary sectional view, similar to Figure 5, but including all the parts of Figures 6 through 16.

25 In all these drawings the same reference numbers represent equal or equivalent elements or parts.

With reference to the accompanying drawings, 1 indicates a convenient curved stretch or conduit part of the musical wind instrument which preferably is chosen situated at the angle or curve extending downwards during the normal position of use of the instrument.

30 Said conduit part 1 is provided with a tubular projection 1a which is shown in Figures 1 and 5. The interior thereof provides near the mouth two internally threaded portions 19 and 21 of different diameter.

35 Said conduit part 1 is provided with a tubular projection 1a which is shown in Figures 1 and 5. The interior thereof provides near the mouth two internally threaded portions 19 and 21 of different diameter.

35 Into the interior of the conduit part 1 of the instrument, there is placed a tubular piece 2. The tubular piece 2 has an arcuate part and is provided upon one of the sides with a plurality of transversal cuts 2a that define openings for the passage of liquid; each cut 2a extends approximately over one-half of the circumference of said tube. The tubular piece 2 forms a succession of tubular stretches, each entering partially into the next following one, leaving in each cut 2a a crescent shaped space as may be seen in Figure 4.

45 Underneath the tubular piece 2, there is placed a channel structure piece 3 which has an arcuate part and which has a semi-circular cross section and is provided with a plurality of orifices or perforations 3a at the base 50 for the passage of liquid. The orifices 3a are shown in Figure 4. The channel structure 3 partially surrounds the tubular piece 2 and has an intermediate section adjacent the tubular projection 1a for the discharge thereto of saliva liquid.

55 Immediately beneath the channel structure piece 3, there is placed an absorbent or hygroscopic material 4 (Figure 5), which might be a sponge or some similar suitable material which in volume must not pass over the end of the arrow "a" of Figure 3. The absorbent material 4 has been shaded in Figure 5.

60 To the interior of said tubular projection 1a, there is connected a hollow tube 5, which is provided near its upper end with a thread 18 with which it engages the thread 19 of the tubular projection 1a. Near the lower end, the tube 5 is provided with a discharge opening including a cut or slot 20 for discharging saliva which might have passed through the absorbent material 4; said cut 20 is elongated and thereby serves furthermore for the mounting of the tube by means of a screwdriver.

65 In the proximity of said cut, the above mentioned tube 5 has different cooperating orifices 20a for the discharge of accumulated saliva.

Concentrically with the tube 5, a hollow tubular structure or mouthpiece 7 is connected, by means of the thread 21 of greater diameter, to said tubular projection 1a.

Said mouthpiece 7 carries externally an extension tube 22a which is threaded laterally at 22. A support, generally indicated at 6, forms part of another stationary portion or member 22b of the instrument, and thus the support 6 is also stationary with respect to the instrument. A coupling 22c is connected to the support 6, and the coupling 22c may be removably threaded onto the thread 22 of the extension tube 22a of the mouthpiece 7, to immobilize the mouthpiece 7. When the coupling 22c is applied, the mouthpiece 7 cannot move. When the coupling 22c is released from the thread 22, on the other hand, the mouthpiece 7 may be removed off the instrument.

Internally, the mouthpiece 7 has adjacent to the walls thereof of three equidistant tubes 8, 9 and 10 between which the tube 5 is placed as may be seen in Figure 9. Of said three tubes, the tube 8 is an air vent with an outlet to the exterior, whereas the tubes 9 and 10 have their openings stepped and their purpose is that of acting as ducts for automatic saliva discharge. The mouthpiece 7 is open at the lower end or base.

To the base of the mouthpiece 7, there is threaded a hollow tubular coupling piece 11 which is open at both ends. Said coupling piece has an external annular flange 23a with two channels 23 and 24 which are coincident with above mentioned discharge tubes 9 and 10.

The coupling piece 11 has a lower external thread 25 to which there is threaded a tubular valve support 12. Said tubular support 12 comprises an upper funnel-shaped part and a lower cylindrical part 26 of reduced diameter. The lower part 26 has two opposed slots 27 and, offset therefrom at a 90° angle, an air vent orifice 28. At the base, the support 12 has an internal flange 12a which forms a seat for a compression spring 15, and a discharge opening 12b. On the interior of said lower part 26 of the support 12 there is supported displaceably a movable plug 13. Said plug 13 is connected to a movable plug carrier 14 which has an orifice for the passage of a pin 17. The movable plug 13 normally closes the lower end of the coupling piece 11, thereby closing the lower end of the mouthpiece 7. The plug 13 is manually movable downwardly against the force of the spring 15, to open the lower end of the coupling piece 11 and thereby of the mouthpiece 7, for the discharge of liquid accumulated inside the mouthpiece 7.

A movable tubular end piece 16 is provided that comprises an upper cylindrical part which is adapted to telescope onto the lower part of the mouthpiece 7, as shown in Figures 1 and 17, and has a lower part of reduced width that surrounds the tubular support 12 and carries said pin 17. The pin 17 passes through the end piece 16, the slots 27 and the orifice of the plug carrier 14. Holes 16a are provided in the movable end piece 16 which form passages for air and saliva, and the end piece 16 has in its base a bottom discharge opening 16b.

The operation of the above described device is as follows:

Insufflated air which flows in the direction indicated by the arrows of Figures 2 and 3 carries with it a certain quantity of saliva. The saliva will pass through the crescent shaped cuts 2a of the tubular piece 2 and will proceed to the channel structure piece 3 wherefrom it will issue through the orifices 3a at the bottom thereof and will be absorbed by the hygroscopic material 4 disposed beneath the channel structure piece 3 at the entry of the tubular projection 1a. Once the absorbent material 4 is saturated, however, the saliva will begin to drip and fill the tube 5. Through the slot 29 in the base of the tube 5, the saliva will pass into the coupling piece 11 from which it will be discharged into the interior of the valve support 12. The valve support 12 will form the

base of a collecting receptacle the walls of which are those of the tube 7.

For emptying the receptacle, it will be sufficient to displace downwardly by a sliding motion the end piece 16 whose pin 17 will carry with it the plug 13. Movement of the plug 13 will permit the saliva to flow through the discharge opening 12b of the valve support 12 wherefrom it will pass to the exterior through the opening 16b in the base of the end piece 16.

Should the performer, however, forget to empty the receptacle in this manner, an automatic discharge system which has been provided in the device will still arrange for the saliva discharge. The automatic system consists of the tubes 9 and 10 which reach the exterior through the external channels 23 and 24 of the coupling piece 11.

Although a specific embodiment of the invention has been described, and been shown in the drawing, it should be noted that the invention may be realized in modified form, and adaptations of the arrangements herein disclosed may be made, as may readily occur to persons skilled in the art without constituting a departure from the spirit and scope of the invention as defined in the objects and in the appended claims.

Having thus described the invention, what is claimed new and desired to be secured by Letters Patent is as follows.

1. A device for collecting and discharging saliva, for use in connection with a musical wind instrument having a conduit part conducting the air and a tubular projection communicating with said conduit part, comprising in combination a tubular piece disposed inside said conduit part and having a series of transversal cuts defining openings for the passage of liquid, a channel structure partially surrounding said tubular piece and defining perforations for the passage of liquid, said channel structure having an intermediate section adjacent said tubular projection for the discharge thereinto of the liquid, a tube connected with one end to said tubular projection and extending therefrom and having near its other end a discharge opening, a tubular structure surrounding said tube and being connected with one end to said tubular projection, a movable plug normally closing the other end of said tubular structure and being operable to open it for the discharge of liquid accumulated on the interior of said tubular structure, a tubular support connected to said other end of said tubular structure and supporting said movable plug on its interior and having slots, said tubular structure having on its interior a plurality of ducts adjacent the inner wall of said structure bypassing said plug for discharging liquid when the plug closes the tubular structure and having a further duct terminating outside said structure for the intake of air when said structure is closed by the plug, means for moving said plug comprising a movable end piece normally in position surrounding said tubular support and being longitudinally movable from and to said normal position and including a pin protruding through said slots and engaging said plug whereby upon movement of said end piece the plug will be moved to uncover said tubular structure for the discharge of liquid from said tubular support.

2. In a device as claimed in claim 1, together with, a body of absorbent material disposed in said conduit part between said channel structure and said tubular projection.

3. In a device as claimed in claim 1, said conduit part of said instrument being bent and said tubular piece and channel structure having each an arcuate portion disposed in said bent conduit part.

4. In a device as claimed in claim 1, said tube being threaded into said tubular projection, the discharge opening of said other end of said tube being elongated and thereby arranged to receive the end of a screw driver for turning said tube about its axis for threaded engagement with said tubular projection.

5. A device as claimed in claim 1, said instrument having a stationary member, said tubular structure having an extension operable to be connected to said member of the instrument for immobilization of said tubular structure.

6. In a device as claimed in claim 1, said tubular support and said end piece having lateral openings for the passage of air.
